UNITED STATES PATENT OFFICE.

CHARLES W. SQUIRES, OF BEVERLY, MASSACHUSETTS.

TRACK-SWITCH.

1,244,138.

Specification of Letters Patent. Patented Oct. 23, 1917.

Application filed August 27, 1915. Serial No. 47,579.

To all whom it may concern:

Be it known that I, CHARLES W. SQUIRES, of Beverly, in the county of Essex and State of Massachusetts, a citizen of the 5 United States, have invented a new and useful Improvement in Track-Switches, of which the following is a specification.

My improvement relates to a switch operating mechanism of a kind now well known 10 and in use upon many electric railways, and it is an improvement upon Letters Patent No. 1,080,730 issued to me December 9, 1913.

In these devices as heretofore constructed it is customary to support the mechanism 15 upon the trolley wire, thus bringing considerable strain upon the wire and placing the mechanism where in case of any accident it is difficult to reach.

My present invention provides a remedy 20 for this difficulty in that while the trolley wire carries an apparatus of light weight for closing a circuit at the proper time, the operating mechanism for throwing the track switch may be located upon a post or other 25 suitable support at a distance both from the trolley wire and if desirable from the track and within easy reach.

No claim is made in this case for the circuit closing mechanism mounted on the trolley wire as the subject-matter of this portion 30 of my invention is included in another application.

As will be understood by electricians upon 35 reading this specification, my invention may be embodied in a variety of forms. My preferred embodiment, however, is shown in the drawings, in which—

Figure 1 is a front elevation of a device 40 for operating the track switch mechanism;

Fig. 2 being a side elevation thereof.

Figs. 3, 4 and 5 are sections on lines 3—3, 4—4 and 5—5 of Fig. 1.

Fig. 6 is a side elevation, partly in section, 45 of the actuator and its connecting parts.

Figs. 7 and 8 are sections on lines 7—7 and 8—8 of Fig. 6.

Fig. 9 is a diagrammatic view showing the 50 circuits.

As shown in the drawings, the device comprises five electro-magnets with appropriate 55 connections which will be described below. Two of these magnets A and B are in the track switch throwing circuit, the track switch being thrown in either direction ac-

cording to which coil is energized. The coil 55 C is the trolley solenoid which is always connected with the trolley wire and by which the switch c is moved to make connection through either the coil A or coil B. In its normal position this switch being 60 hinged as below described, makes connection through the coil A. When the magnet C is sufficiently energized, as by the full car current, the switch c is thrown so as to cause the current to pass through the magnet B. 65

It will be understood that the track switch is one of ordinary character which is moved in either direction by appropriate electromagnets, one magnet being connected in circuit with the magnet B and the other with 70 the magnet A.

In order that the current by which the track switch is being operated may have a proper time in which to act upon the switch to throw it, I provide the coil D, which I will 75 call a time limit coil, and by means of which the time during which the car magnet is energized is determined or limited, this being accomplished in the form of my invention shown by means of a tilting table F, which 80 when the coil D is energized is lifted at one end and consequently causes a circuit closer to run from that end of the tilting table to the farther end where it makes electrical connection through the coil E which I call 85 the circuit breaker coil. When the coil E is energized its core is lifted or drawn into it and lifts a circuit closer forming part of the main circuit, thus breaking the connection in the main circuit and allowing all the 90 parts to resume their original or inoperative position.

In the general adjustment and operation 95 of the apparatus, therefore, the coil E is only energized after the track switch has been thrown.

In Figs. 6, 7 and 8 is shown the mechanism which is mechanically operated by the car and is mounted on the trolley rail. As the mounting of this mechanism is the same 100 as in my patent referred to it is not shown in full. It comprises a baseboard G made of wood or other like insulating material and an arched frame G¹ which acts as a support for certain of the parts which are 105 mounted therein and are insulated therefrom. Preferably the frame itself is made of insulating material and the whole may

be provided with a cover (not shown), if thought best. The frame G^1 is supported on the baseboard G by angle irons g , one at each end attached to the baseboard G by cross pieces g^1 , preferably metallic, these cross pieces having openings g^2 through which pass attaching bolts g^3, g^4 . The baseboard G is preferably mounted on a metal plate G^2 which extends the length of the baseboard and which is electrically connected with the trolley wire, not shown. The plate G^2 is also electrically connected with a contact finger G^4 , as, for example, by means of a wire g^5 , for which the bolt g^3 serves as a binding screw. G^5 is a carrier to support and operate the contact finger G^4 . This carrier as shown comprises a heavy wire, one end of which is bent at right angles to the body thereof and is mounted to swing in bearings g^6 , the other end being also bent at right angles to the body and then bent back on itself to form a loop G^7 . As matter of convenience one end of the contact finger G^4 is bent around the first named end of the carrier G^5 so that it is free to swing loosely with relation thereto and it is passed through the loop g^7 so that it may be lifted or pulled down by the movement of the swinging support.

H is an actuator or lever mounted on the baseboard G to swing with relation thereto, the baseboard and the parts below it being slotted so that the actuator may pass down through them into position to be struck by the trolley wheel mounted on the passing car. This actuator has a toe piece h suitably placed to engage the under surface of the loop portion g^7 of the carrier G^5 and lift it and the contact as the trolley passes beneath the instrument.

J is a terminal mounted from the frame G^1 and suitably insulated therefrom and connected by the wire j with the box apparatus as described below. Preferably I insert in the wire j a resistance j^1 to reduce the current which passes by it to the coils in the box, this wire j passing out through a suitable opening in the frame G^1 .

The terminal J is located to be struck by the contact finger G^4 during its downward movement after it has been actuated by the trolley lever H .

In order to prevent the contact finger from making two contacts with the terminal J one upon its being lifted and the other upon its falling, I have provided a cam plate J^1 which is mounted upon the baseboard G and supported at its top from the frame G^1 so that it shall be insulated. In this cam plate is a slot J^2 and through this slot projects the end of this contact finger G^4 , the slot being partly diagonal in shape at its lower end and somewhat wider than the end of the contact finger, its upper end being vertical and narrow. The lower por-

tion of the slot J^2 is about the middle of the cam plate J^1 so that the end of the contact finger normally rests in the angle at the lowest part of the slot. It will be seen that upon the contact arm being lifted by the swinging support it will strike the upper surface of the slot and its joint being loose it will be guided laterally along the upper edge of the slot as shown at 1, and into the vertical portion of the slot as shown at 2 (see Fig. 8). Thus it will be seen that it will pass by the end of the terminal J which as shown in Fig. 8 is bent somewhat to conform to the shape of the slot J^2 . When it is released, however, upon the passing of the trolley by the actuator H , and the consequent dropping of the actuator into the position shown in Fig. 6, the tendency of the contact G^4 will be to drop vertically, being guided by the vertical portion of the slot J^2 until it strikes the slanting surface thereof, when it will engage the bent portion of the terminal J , its end g^8 being enlarged for the purpose, as shown at 4 in dotted lines, Fig. 8, and make the necessary contact which will be of short but appreciable duration, and will cause the closing of the main circuit as below described.

The box upon which the main mechanism is mounted comprises a back plate N , a horizontal top plate M and a horizontal bottom plate M^1 , both attached to the back plate, the horizontal plates being supported by suitable brackets m and posts m^1, m^2 .

Upon the plate M are mounted the coils A and B and upon the plate M^1 are mounted the coils C , D and E . Cross bars m^3, m^4 are provided connecting the posts m^1 and the posts m^2 , respectively, and serve also to support certain portions of the circuits.

The wire j runs to the box which as stated above may be at any reasonable distance from the switch point and therein is connected to a fuse K in the ordinary way, from which fuse it continues to the pin c^1 upon which is pivoted the switch c . As shown in Fig. 1 the free end of the switch engages the point a which is connected by the wire a^1 with a plate a^2 which in turn is connected by the wire a^3 with the coil A . The other end of the coil A is connected by the wire A^1 with an electro-magnet by means of which the switch is pulled in one direction.

The coil A has a core A^2 which carries a cross bar A^3 so that when the coil A is energized as above, the core A^2 will be drawn within the coil and will lift the cross bar A^3 , making contact with the strip A^4 and the plate a^2 , the purpose of which will be below described.

L is a wire connected to the trolley wire and forming part of the main circuit. At l the circuit divides, one portion of it comprising the wire C^1 running to the coil C

and thence by wire C² to the plates forming the terminal from which the trolley is to draw its current for the car circuit. The coil C thus is fully energized only when the car is drawing its full current.

The other branch of the wire L comprises a connection D¹ with the fuse K¹ from which the current passes by wire D² to the hook D³ mounted on the plate M¹ and to which is connected a fuse wire D⁴, this fuse being of the kind described in an application filed by me February 4, 1914, Serial No. 816,498, issued as Patent No. 1,199,831 on October 3, 1916, and comprising two short lengths 15 of platinum wire, the contacting ends of which are bent at right angles as at d and soldered together with a solder fusible at low temperature. The farther end of this fuse is hooked over a spring hook D⁵ mounted on top of the coil D and is connected with one end of the said coil, the other end of the coil being connected by wire D⁶ to the plate D⁷ by which electrical connection is made with the staple shaped wire D⁸. This 25 staple D⁸ passes down through the plate M, front cross bar m³ and plate D⁷ and its top rests on the plate M.

At the rear of the plate M is similarly mounted another staple shaped wire D⁹ and 30 a metallic weighted cross plate D¹⁰ normally rests on the staples D⁸ and D⁹, connecting them electrically. To the lower ends of the staple D⁹ is attached a plate D¹¹ which is connected by the wire D¹² with a contact 35 plate F¹. The purpose of this plate F¹ will be later described. The staple D⁹ is also in contact with the strip A⁴. The strip A⁴ is mounted on the under side of the cross bar m⁴.

40 The plate a² is connected with the switch terminal a as above described, and it will be seen that when the coil A is energized by the engagement of the contact finger G⁴ with the terminal J the core A² of the coil A will be lifted, thus lifting the bar A³ and closing the circuit between the plate A⁴ and the plate a². When this occurs a circuit is established from l through the fuse K¹, wire D², fuse wire D⁴, the coil D, wire D⁶, staple D⁸, cross plate D¹⁰, staple D⁹, strip A⁴, plate a², wire a³, coil A, wire A¹ and the switch magnet to the ground, so that the switch magnet is given sufficient energy to throw and hold the switch until 55 this circuit is broken.

The circuit breaking mechanism is as follows: The coil D has a core F² which when the coil D is energized will be drawn into it. To the lower end of this core F² is pivotally attached a tilting table F by means of a contact arm F⁴. F⁵ is a stud on which this carriage is pivotally mounted so that, while in its normal position, its free end is lower than its pivoted end. When it is 60 lifted by the attraction of the core F² by coil C its free end will be higher than its pivoted end, and its contact arm F⁴ will make contact with the plate F¹. The stud F⁵ is electrically connected by the wire f with one end of the coil E, the other end E² of this coil being grounded by an independent ground E¹ to which the wire E² runs. Within this coil E is a comparatively short core E³, the upper end of which is provided with a rod E⁴ made of insulated material 70 which is connected to the cross plate D¹⁰. When the coil E therefore is energized the cross plate D¹⁰ will be lifted and the circuit will be broken between D⁸ and D⁹. This being a part of the main circuit the entire 75 apparatus will resume its normal position.

In order, however, that the main circuit be not broken until the current has had full opportunity to operate and hold the switch, the tilting table has mounted upon one side 80 of it a metallic strip f¹ which forms an electrical connection between contact arm F⁴ and a casting or plate f² as shown in Fig. 5. Upon the other side of the tilting table is a corresponding casting or plate f³ 85 which is electrically connected with the stud F⁵. Above the tilting table is mounted a runway F⁶ comprising two narrow strips supported on posts F⁷. Within this runway is carried a rotary circuit closer F⁸, or 90 pair of comparatively heavy metallic wheels connected by a metallic axle, the diameter of the wheels being sufficient to enable it when at the end of the tilting table nearest the stud F⁵ to ride upon the plates f², f³ 95 and so close the circuit between the arm F⁴ and the stud F⁵, and hence through the coil E.

Thus when the coil D is energized by the lifting of the bar A³ which closes the main 105 circuit, its core F² lifts the free end of the tilting table at which moment the rotary circuit closer F⁸ begins its descent of the runway F⁶ until finally it brings up on the plates f², f³, and closes a divided circuit through 110 E, thus causing its core E³ to be lifted, and with it the rod E⁴ and the cross plate D¹⁰, and breaking the main circuit at D⁸ and D⁹. The apparatus is then set for the next car.

Suppose the next car is to pass over the 115 switch with the switch thrown in the other direction. The car circuit is closed through the car so that the car passes the mechanism under power. The coil C receives the full current through L so that the coil C is 120 energized by more current than in the former case. It was stated before that the current passing through the wire L divided at l, a portion of it going through the wire C¹ to the coil C. A portion of the current 125 from L whether it be the ordinary light or air brake operating current, or the full current which operates the car, always passes through the coil C. In order that the coil C may not operate to throw the switch c 130

with the light or brake operating current it is provided with an armature C³ which armature is held at the lower end of a rod C⁴ of insulating material. Through the coil 5 passes a tubular guide C⁵ and to a head C⁶ mounted on top of the coil C is attached an adjuster C⁷ comprising a plate having stepped surfaces c² on its upper edge. This adjuster C⁷ is capable of horizontal adjustment by means of a slot c³ and a screw c⁴ and to the rod C⁴ is attached a pin c⁵ which when the coil C is not energized rests on one of the steps c² so that while the armature will be lifted when the full current 10 passes through the coil C it will remain in its lowest position when a less current passes through the coil. Thus in first use of the mechanism above described, when the car passes the mechanism without current the 15 armature and its rod will not be lifted and the switch c will not be thrown but when the car passes under power the full current will pass through the coil C, the armature will be lifted and the upper end of the rod 20 C⁴ will strike the switch c and lift it from the pin a into engagement with the pin b. In this case on operating the contact finger G⁴ the impulse will pass by the wire f as before to the switch pivot c¹ and from thence 25 through the switch c to the contact b through the wire b¹ to the plate b², from thence by the wire b³ to the coil B and by wire B⁴ to the switch operating solenoid and the ground.

30 The cross bar B³ will be lifted by the core B² of the magnet B when it is thus energized and will close the circuit from l, K¹, etc., as before, to the staple D⁸, cross plate D¹⁰, staple D⁹, strip A⁴, to the cross bar B³, plate 35 B², wire b³, to the coil B, and by wire B⁴ to the magnet on the other side of the track switch. The current upon energizing the solenoid D will raise the tilting table F as before, making connection through the 40 plate F¹ and plates f², f³, by means of the rotary closer F⁸ so that at the proper time the coil E will be energized and the main circuit broken as before.

I prefer to make the rod E⁴ with flat sides 45 and to provide means such as the wire guides e to keep the cross bar D¹⁰ in proper alignment. As shown the upper end of E⁴ is provided with a weight e¹ to keep the cross bar D¹⁰ normally in contact with D⁸ and D⁹.

In order that the tilting table when out 50 of action may be supported in proper relation to the coil D I have shown a rest such as the angle iron F⁹ attached to the plate N on which the free end of the tilting table 55 may rest.

To support the contact plate F¹ and the stud F⁵ I prefer to provide a plate F¹⁰ of insulating material attached below the plate 60 M¹ by brackets m, and the tilting table car-

ries a yoke F¹¹ which hangs on the stud F⁵ thus connecting mechanically the tilting table with the stud. This yoke is electrically connected with the plate f³. A spring F¹² compressed between the plate F¹⁰ and the yoke F¹¹ holds the tilting table in proper position so that the contact arm F⁴ will make proper contact with the plate F¹.

The above is a description of the preferred embodiment of my invention but I do not mean to confine myself to such embodiment. Any one skilled in the art will realize upon reading the foregoing description that other means than those shown and other arrangements of circuits can be adopted to accomplish the desired results, the main features of which are the closing of the circuit at the contact arm which can only be momentary and the closing of the circuit through the track switch instrument which closing is for a predetermined period of time—time sufficient to properly energize the track switch instrument. The fact that the circuit at the contact arm can only be closed momentarily at the moment when the actuator is released by the trolley wheel makes it possible for the passing car to stop below the trolley carried instrument without injury to the operating mechanism which is impossible in any electric track operating instrument now known to me, such stoppage in other instruments frequently burning out the line.

It is evident also that while the above-described mechanism is shown as adapted for the purpose of energizing either one of two track switch magnets it may be used to energize either one of two magnets adapted to operate some other mechanism than a track switch.

What I claim as my invention is:—

1. In a device of the kind described, an electromagnet, two coils, means whereby the energizing of either coil will cause the energizing of said electromagnet and comprising two circuit closers, one adapted to be operated by each coil and means whereby either coil may be energized comprising a circuit closer and means for operating it to close the circuit momentarily and a resistance located in circuit with said circuit closer and one of said coils whereby an impulse of current of low amperage will be sent through either one of said coils to operate its circuit closer.

2. As a means for temporarily energizing either of two electromagnets, a feed wire, two coils, one connected to each electromagnet and normally out of connection with said feed wire, means for energizing either coil momentarily, two circuit closers each operated by one of said coils to close a circuit including said feed wire and one of said electromagnets and means for breaking said circuit comprising a circuit breaker

and means for operating it whereby said circuit will be broken a predetermined time after said circuit has been closed.

3. As a means for temporarily energizing either of two electromagnets, a feed wire, two coils, one connected to each electromagnet and normally out of connection with said feed wire, means for energizing either coil momentarily, two circuit closers each operated by one of said coils to close a circuit including said feed wire and one of said electromagnets and means for breaking said circuit comprising a circuit breaker and means for operating it whereby said circuit will be broken a predetermined time after said circuit has been closed, said means comprising a pivoted table, means for lifting one end thereof, a traveling circuit closer carried by said table and adapted to travel thereon when said end has been lifted, terminals located in the path of said traveling circuit closer whereby said terminals may be electrically connected upon engagement by said traveling circuit closer, 25 said terminals forming part of a circuit adapted when closed to operate said circuit breaker.

4. As a means for temporarily operating either one of two electromagnets, a feed wire, two coils, one connected to each electromagnet and normally out of circuit with said feed wire, means for energizing either coil momentarily, two circuit closers each operated by one of said coils to close a circuit including said feed wire and one of said electromagnets, and means for breaking said circuit comprising a circuit including a coil, a movable core operated by said coil when energized, a circuit breaker 40 member adapted to be operated by said core and means operable upon the closing of the circuit through one of said electromagnets whereby said circuit will be closed and said circuit breaker member operated.

45 5. In a device of the kind described, two coils each connected to an electromagnet, means for energizing either coil momentarily comprising a source of current and a switch adapted to connect said source of current with either coil and means for operating said switch comprising a feed wire carrying a variable current, a coil in circuit with said feed wire, an armature adapted to be attracted by said coil, means connected 50 to said armature adapted to engage said switch when said armature is attracted by said coil and means to adjust the distance of said armature from said coil whereby it will only be operated to operate said switch 55 when a predetermined amount of current is passing through the feed wire.

6. In a device of the kind described, two coils each connected to an electromagnet, means for energizing either coil momentarily comprising a source of current and a

switch adapted to connect said source of current with either coil and means for operating said switch comprising a feed wire carrying a variable current, a coil in circuit with said feed wire, an armature adapted to be attracted by said coil, means connected to said armature adapted to engage said switch when said armature is attracted by said coil and means to adjust the distance of said armature from said coil whereby it will only be operated to operate said switch when a predetermined amount of current is passing through the feed wire, said adjusting means comprising an adjusting plate having an irregular upper edge mounted on said coil to be adjusted laterally with relation thereto, a rod mounted on said armature and a stop pin mounted on said rod to engage the upper edge of said adjusting plate.

7. In a device of the kind described, comprising operated track switch solenoid circuits, means for closing the circuit through either of them, a slowly moving circuit closer means operable by either track switch solenoid circuit whereby said slowly moving circuit closer will be operated and a circuit breaker adapted to break said track switch solenoid circuit and means for operating said circuit breaker operable upon the closing of the circuit through said slowly moving circuit closer.

8. In a device of the kind described, means for energizing either one of two electromagnets comprising two coils, one in circuit with each electromagnet, means for temporarily energizing one of said coils, means operated by such coil when temporarily energized to permanently energize its electromagnet, a time limit mechanism, electrical means for operating said time limit mechanism comprising a circuit closer and means operated by said time limit mechanism whereby the main circuit will be broken.

9. A track switch-operating circuit comprising a car operable means momentarily to close said circuit and circuit-locking means comprising a magnet coil, a normally open electric circuit switch and a feed wire operable to hold said track switch-operating circuit in closed position, and a branch circuit with a magnet coil operable momentarily to interrupt the flow of current through the track switch-operating circuit whereby the release of said circuit-locking means will be effected, and automatic means operable by the track switch-operating circuit to energize said branch circuit within a predetermined time limit, substantially as set forth.

10. A track switch-operating circuit comprising a car operable means momentarily to close said circuit and circuit-locking means comprising a magnet coil, a normally open electric switch and a feed wire operable to

hold said track switch-operating circuit in closed position, and a branch circuit with a magnet coil operable momentarily to interrupt the flow of current through the track-
5 switch-operating circuit whereby the release of said circuit-locking means will be effected, and automatic means operable to energize said branch circuit within a predetermined time limit, substantially as set forth.

10 11. A normally-open track switch circuit comprising two track switch magnets, trol-

ley-operated means to close the circuit through either of said magnets at will, a normally-open auxiliary circuit having a ground connection distinct from the track 15 switch circuit and means operable automatically to close said auxiliary circuit a predetermined time after the closing of said track switch circuit, and means whereby the closing of said auxiliary circuit will cause the 20 breaking of said track switch circuit.

CHARLES W. SQUIRES.
